TAPE REEL

Wilbur R. Gemmel, Wheaton, Ill., assignor to Teletype Corporation, Chicago, Ill., a corporation of Delaware

Application July 29, 1943, Serial No. 496,531

8 Claims. (Cl. 242—68)

This invention pertains to tape reels and more particularly to adjustable tape reels.

Existing types of tape reels are made for a single specific size tape roll and, therefore, it is necessary to change reels for each different sized tape roll, which necessitates the use of more than one reel.

In the operation of printing telegraph apparatus it is frequently necessary to use more than one size tape rolls, at different times. Accordingly, a single reel was desired which was capable of adjustment so as to accommodate more than one size width roll of tape.

The principal object of the present invention is to provide a tape reel which is capable of accommodating more than one width of tape roll.

The tape reel according to the present invention is formed of a disc having a central opening, which supports the tape roll. A hub, having two angularly displaced supports, is rotatably mounted on a spindle which is mounted securely in a tape carriage. The disc may be fastened to either of the two supports, depending on the width of tape which is being used. One of the supports or a stem arising from the hub, is used as a tape roll positioning means, depending upon which of the two supports the tape roll is mounted. An arm is mounted to the tape carriage which is spring urged to retain the tape within the tape carriage.

A more complete understanding of the invention may be had from the following description taken in connection with the accompanying drawing, in which:

Fig. 1 is a fragmentary plan view, partly broken away, of the tape reel embodying the present invention;

Fig. 2 is a sectional side view, taken approximately on the line 2—2 of Fig. 1;

Fig. 3 is an enlarged perspective view of the hub of the tape reel;

Fig. 4 is a fragmentary plan view, partly broken away, of the tape reel supporting a narrower width of tape than that shown in Fig. 1, and

Fig. 5 is a sectional side view, taken approximately on the line 5—5 of Fig. 4.

The tape container, as shown in Fig. 2, comprises a cage which is formed of a base 11 having secured thereto, by means of screws 12, a plurality of brackets 13. A spindle 14 is securely fastened to the base 11, centrally of the brackets 13, by means of nuts 16 which are positioned on either side of the base 11. At the top of the brackets 13, set inwardly and held in place by

screws 17, is a guide rail 18, the purpose of which will be explained later. A bracket 19 is secured to the base 11, by means of a screw 21, at the top of which is pivotally mounted an arm 22 which is urged downwardly toward the top of the guide rail 18 by a leaf spring 23, a leather stop (not shown) limiting its downward movement.

The hub, as shown in Fig. 3, comprises a stem 24 on which is mounted a pair of supports 26 and 27, which are spaced apart by a spacer 28, and which are angularly displaced 90° with respect to each other. The hub unit is held together by means of screws 29. The supports 26 and 27 each have a threaded hole 31 toward each end of each support. As shown in Fig. 2, the stem 24 has a bored recess 32 extending almost all the way to the top, designed to be slightly larger than the outside diameter of the spindle 14.

A disc 33, Fig. 1, is formed with a central opening 34 which has the same contour and is slightly larger than the supports 26 or 27, and a series of openings 36, the latter of which are designed to reduce the weight of the disc. The disc 33 has a pair of countersunk holes which are aligned with the threaded holes 31 of either of the supports 26 or 27.

Figs. 1 and 2 show the tape reel holding a roll of wide tape 37, having a cardboard center hub 38. The central opening 39 in the hub 38 is relatively large, as is the custom in the winding of relatively wide tape. The loose end 41 of the tape is shown at the left in Fig. 1.

Figs. 4 and 5 are similar to Figs. 1 and 2, with the exception that a roll of narrow tape 42 is supported in the tape container. As is the usual custom with narrow width tape, a wooden hub 43, having a small central opening 44, slightly larger than the outside diameter of the stem 24, serves as the center for the roll of tape. Otherwise, as previously mentioned, these views are similar to Figs. 1 and 2, and similar identification numerals have been used.

When it is necessary to use a wide tape in the printing telegraph apparatus the disc 33 is fastened securely to and just on top of the lower support 27 of the hub, by means of screws which enter the threaded holes 31 in the support and those aligned therewith in the disc. The disc 33 is now constrained to rotate with the hub, which is rotatably mounted on the spindle 14. The tape roll 37 is then placed on the disc 33, the central opening 39 of the tape roll hub 38 fitting over the top support 26 which acts as a positioning means. The arm 22, urged downwardly by the leaf spring 23, retains the roll of

tape on the hub and positioned within the tape container while it is being unwound.

As previously mentioned, a guide rail 18 is secured to the brackets 13. The guide rail is used to prevent the tape from falling off from the edge of the disc 33 in the event that there is a slack in the tape. This is accomplished as the circumference of the guide rail 18 is less than that of the disc 33. The tape end 41 passes through an opening whereat the guide rail 18 has been cut away, as seen on the left side of Fig. 1.

In the event that a narrow width tape is used, the disc 33 is unscrewed from the support 27 and raised until it is just above the top support 26. The disc is then turned through 90°, so that its two countersunk holes are aligned with the two threaded holes 31 in the support, and the disc is then screwed into place. The roll of narrow tape 42 is placed upon the disc, the central opening 44 in the hub 43 of the tape roll being placed on stem 24, thus correctly positioning the roll of tape upon the disc 33 and in the tape carriage.

The spaced supports 26 and 27 have been displaced angularly in respect to each other, to make it possible to tighten the screws entering the threaded holes 31 from above. If there were no angular displacement it would be very difficult to tighten the screws, especially when the disc 33 was secured to the lower support 27.

In the above descriptions, it is necessary to pivot arm 22, up and against the tension of the leaf spring 23, so as to allow the roll of tape to be put in place.

As previously mentioned, the supports 26 and 27 are separated by means of a spacer 28, with the entire unit being secured together by means of screws 29. This makes it possible to remove the spacer 28, and substitute one of a different height. This may be necessary if a different width tape is used than as shown in Figs. 4 and 5, making it necessary to raise or lower the top support 26.

By maintaining constant the size of the central openings 39 and 44 in the roll hubs 38 and 43, respectively, it would be possible to support various width tapes at each of the positions of the disc 33. That is, the support 27 could support any size tape greater in width than the distance between it and the support 28, whereas the support 26 could support any width tape up to the top of the brackets 13, or the arm 22. In so doing, the arm 22 may require a slight redesign.

Although a specific embodiment of the invention has been shown and described, it will be understood that this embodiment is but illustrative and that various modifications may be made therein without departing from the scope and spirit of the invention.

1. In combination, in a tape reel, a hub, a pair of parallel spaced supports secured to said hub displaced angularly to each other, and a disc having a central opening having a peripheral contour corresponding to and slightly larger than the peripheral contour of said supports, said disc being secured to one of said supports to support one width of tape but detachable therefrom and securable to the other of said supports to support a second width of tape.

2. In combination, a tape roll mounting comprising in a unitary structure a tape roll container, a spindle secured within said container, a hub rotatably mounted on said spindle, a pair of parallel spaced supports secured to said hub displaced angularly to each other, a disc having a central opening having a peripheral contour corresponding to and slightly larger than the pe-

ripheral contour of said supports, said disc being secured to one of said supports to support one width of tape but detachable therefrom and securable to the other of said supports to support a second width of tape, and means to retain a roll of tape within said tape container.

3. In combination, a tape reel to accommodate various widths of tape rolls comprising a hub, a stem on said hub, a pair of parallel spaced supports secured to said hub displaced angularly to each other, and a disc having a central opening having a peripheral contour corresponding to and slightly larger than the peripheral contour of said supports, whereby said disc is secured to one of said supports to support one width of tape but detachable therefrom and securable to the other of said supports to support a second width of tape, and the upper of said pair of supports acts as a tape roll positioning guide when said disc is secured to the lower of said pair of supports while said stem acts as a tape roll positioning guide when said disc is secured to the upper of said pair of supports.

4. In combination, a tape roll mounting comprising in a unitary structure a tape roll container, a spindle secured within said container, a hub rotatably mounted on said spindle, a pair of parallel spaced supports secured to said hub displaced angularly to each other, a disc having a central opening having a peripheral contour corresponding to and slightly larger than the peripheral contour of said supports, said disc being secured to one of said supports to support one width of tape but detachable therefrom and securable to the other of said supports to support a second width of tape, an arm pivotally secured to said tape roll container, and a spring urging said arm against said container for the purpose of retaining a roll of tape within said tape container.

5. In combination, a tape reel to accommodate various widths of tape rolls comprising a hub, a pair of parallel spaced supports secured to said hub displaced angularly to each other, and a disc having a central opening, said disc being secured to one of said supports to support one width of tape but detachable therefrom and securable to the other of said supports to support a second width of tape, the central opening in said disc having a peripheral contour corresponding to and slightly larger than the peripheral contour of said supports to permit said disc to be moved past one of said supports so as to be secured to the second of said supports to accommodate a different width of tape.

6. In combination, a tape reel to accommodate various widths of tape rolls comprising a hub, a stem on said hub, a pair of parallel spaced supports secured to said hub displaced angularly to each other, and a disc having a central opening, said disc being secured to one of said supports to support one width of tape but detachable therefrom and securable to the other of said supports to support a second width of tape, the central opening in said disc having a peripheral contour corresponding to and slightly larger than the peripheral contour of said supports to permit said disc to be moved past one of said supports so as to be secured to the second of said supports to accommodate a different width of tape, and the upper of said supports acting as a tape roll positioning guide when said disc is secured to the lower of said pair of supports while said stem acts as a tape roll positioning guide when said disc is secured to the upper of said pair of supports,

7. In combination, a tape reel comprising a hub, a pair of parallel spaced supports secured to said hub displaced angularly to each other, a disc having a central opening having a peripheral contour corresponding to and slightly larger than the peripheral contour of said supports, said disc being secured to one of said supports to support one width of tape but detachable therefrom and securable to the other of said supports to support a second width of tape, and a replaceable spacer on said hub separating said supports, whereby when a different size spacer is used to separate said supports said other of said supports will support a tape different in size from said second width of tape.

10

15

5

8. In combination, in a tape reel, a hub, a pair of substantially rectangular spaced supports secured to said hub, said supports being located in parallel planes and displaced angularly to each other, and a disc having a substantially rectangular central opening corresponding to and slightly larger than the peripheral contour of said supports, said disc being secured to one of said supports to support one width of tape but detachable therefrom and securable to the other of said supports to support a second width of tape.
